Primary Examiner — Patricia A Palasik(74) *Attorney, Agent, or Firm* — Fitch, Even, Tabin & Flannery LLP**CLAIM**

I claim the ornamental design for a receiver for a bottling machine, as shown and described.

DESCRIPTION

FIG. 1 is a bottom perspective view of a receiver for a bottling machine of my new design;

FIG. 2 is a top perspective view of a receiver for a bottling machine of my new design;

FIG. 3 is a front elevation view of a receiver for a bottling machine of my new design;

FIG. 4 is a left side elevation view of a receiver for a bottling machine of my new design;

FIG. 5 is a top view of a receiver for a bottling machine of my new design; and,

FIG. 6 is a bottom view of a receiver for a bottling machine of my new design.

The rear and right side elevation views are omitted as they are mirror images to the front and left side elevation views, respectively.

The broken lines in the drawings depict portions of the receiver for a bottling machine which form no part of the claimed design.
